SHUTTER-FOLD AWNING

John Henry Kadleck, Pasadena, Calif.

Application October 18, 1946, Serial No. 704,148

2 Claims. (Cl. 160—183)

1

This invention relates to a shutter-fold awning, which may be constructed of any durable material such as wood, metal, plastics and the like, and can be made to fit any size window, door or porch, or any place where an awning is desired, providing there is ample space for the erection thereof.

An object of the invention is to provide a rigid awning that may be folded into closed, inoperative position, in the same manner as ordinary window shutters are closed over the window opening.

Another object of the invention is to provide an awning that is simple in construction, durable and efficient in operation and can be inexpensively manufactured.

With the above and other objects and advantages in view, the invention consists of the novel details of construction, arrangement and combination of parts more fully hereinafter described, claimed and illustrated in the accompanying drawings in which:

Figure 1 is an exterior elevational view of an embodiment of the invention;

Figure 2 is a sectional view on the line 2—2 of Figure 1;

Figure 3 is an elevational view of the supporting members of the device; and

Figure 4 is an elevational interior view of the awning in closed or folded position.

Referring more in detail to the drawings, the reference numeral 10 designates the supporting frame which comprises top and bottom and intermediate bows 11. The bows at their ends are joined by cross-bars 12, and reinforcing blocks 13 are interposed between the bows and cross-bars, and are connected thereto in spaced relation to each other.

Secured to the cross-bars at the center thereof in perpendicular relation thereto is the tie board 14 which retains the bows in parallel spaced relation to each other. The bottom and top cross-bars are secured to the lower side of the board 14, but the intermediate cross-bar is secured to the upper side of the board 14.

Secured to the outer surface of the bows 11 in spaced parallel relation to each other are the top slats 15, and the top and bottom edges of the slats form somewhat the same contour as the bows. Secured to the under surface of the bows 11 are the bottom slats 16 which are so spaced that a slat 16 will underlie the space between two upper slats 15. Thus arranged, the slats will prevent the direct rays of the sun penetrating through the awning, but will permit the light to

show through, as well as affording plenty of ventilation. The bows thus form spacers for the top and bottom slats, and the offset relation of the slats provides a perfect sunshade without eliminating all of the light.

The upper cross-bar is secured to the side of the house 17 or other support by hinges 18, thus the frame 10 can be swung outwardly at an angle or be in close contact with the side of the house.

Secured to the top and bottom cross-bars at each end thereof by pivot bolts 19 are the inclined top members 20 of the side frames, and these members follow the inclination of the frame 10. Secured to the upper ends of the members 20 are the vertical end members 21, and the horizontal bottom members 22 secured to the bottom end of the members 20 and 21 form the side frames which are triangular in formation.

Secured to the inner surfaces of the side frames are the inner slats 23, and the outer slats 24 are secured to the outer surfaces of the side frames in offset relation to the inside slats in the same manner as are the slats on the frame 10.

The side frames can be swung into folded position, as shown in Figure 4, and the frame 10 will then lie flat against the side frames. In use, the side frame will be swung outwardly to support the frame 10, and latch 25 secured to the house 30 will engage the headed bolts 26 to retain the sides in operative position. Since the upper and lower cross-bars are secured to the undersurface of the board 14, cutouts 27 are provided at each end of these cross-bars to accommodate the outer bottom slats for the proper spacing thereof.

There has thus been provided an awning that can be folded into closed position, similar to house shutters, and in raised operative position will prevent the direct rays of the sun from penetrating therethrough, while still providing plenty of light and ventilation.

It is believed that from the foregoing description, the construction and operation of the invention will be apparent to those skilled in the art, and it is to be understood that changes in the minor details of construction, arrangement and combination of parts may be resorted to, provided they fall within the spirit of the invention, and the scope of the appended claims.

Having thus described the invention, what is claimed as new and desired to be secured by Letters Patent is:

1. A device of the character described, comprising a supporting frame formed of upper and lower and intermediate bows, cross-bars secured

to the ends of said bows, a tie board connected to said cross-bars at the center thereof, and spacing said cross-bars at the ends and center of said tie board, inner and outer slats secured to said bows in offset relation to each other, means for hinged-ly supporting said frame on a house, and side frames for supporting said frame in inclined relation with the house.

2. The invention as in claim 1 wherein said side frames are pivotally connected to the sup- ported frame, slats are secured to said side frames in offset relation to each other, and means is

provided for retaining said side frames in fixed relation to said house.

JOHN HENRY KADLECK.
